TO SIMMONS COMPANY, OF NEW YORK, N. Y., A CORPORATION OF DELAWARE

FOLDING CHAIR

Application filed September 2, 1927. Serial No. 217,038.

The object of the present invention is to provide a simple, strong and durable construction of folding chair, and the invention consists in the features of novelty herein described, illustrated in the accompanying drawings and particularly pointed out in the claims at the end of this specification.

In the drawings:

Figure 1 is a perspective view of a folding chair embodying our invention.

Figure 2 is a view in side elevation showing the chair in partially folded or collapsed position.

Figure 3 is a back or rear view of the chair after it has been completely folded.

Figure 4 is a view in vertical longitudinal section on line 4—4 of Figure 3.

Figure 5 is a view, upon an enlarged scale, through a portion of the chair seat, this view being taken on line 5—5 of Figure 1.

Figure 6 is an inverted plan view, partially in section, of one corner of the chair seat.

As shown, the back members and front legs of our improved chair comprise a U-shaped frame 10, preferably formed of a single piece of thin steel tubing, the ends of the front leg portions of this frame 10 being fitted with suitable ferrules 11. Between the sides of the frame 10 and near its top extends a brace plate 12. This plate 12 is preferably formed of thin sheet metal with its top and bottom edges curled rearwardly and inwardly as at 13 (see Figure 4), and these inwardly curled or reinforced top and bottom edges of the brace plate have projections 14 that extend beyond the ends of the body portion of the plate and enter holes that are formed in the walls of the sides of the U-shaped frame 10. When the plate 12 has been placed in position between the sides of the U-shaped frame 10, with the projections 14 entering the holes in the sides of the frame 10, the base plate 12 will be held rigidly in place, as by spot welding, as at 15, the reinforced ends of the plate 12 to the sides of the frame 10.

If desired, the top and bottom edges of the brace plate 12 may be further reinforced by wires 16, as shown at the lower portion 50 of the plate 12 (see Figure 4), in which case

the reinforced edges 13 of the brace plate 12 may terminate at the sides of the frame 10 while the wires extend into the side members.

Between the sides of the frame 10 extends the leg-pivot bar or rod 17 that preferably passes completely through the side bars of the frame 10 and has its ends headed or upset as at 17^a. Upon this leg-pivot bar 17 is pivotally mounted the rear legs 20 of the chair, spacing ferrules 18 being interposed between such rear legs and the side bars of the frame 10. As shown, the rear legs 20 are formed of metallic angle bars, the outer flanges 21 of which are perforated to receive the pivot rod 17, and, preferably, reinforcing plates 22 are riveted upon the inner sides of these flanges 21 and are provided with holes through which the pivot rod 17 passes. The flanged portion 23 on each 65 of the rear legs extends inwardly as shown, and preferably the extreme lower ends of such flange portions 23 are bent angularly as at 24 (see Figure 4) to afford a broader bearing where such legs contact with the 70 floor or other surface on which the chair is placed. Between the lower portions of the rear legs 20 extends the brace bar 25 which is preferably an angle bar, one member of which is riveted as at 26 to the inwardly- 75 extending flanges 23 of the rear legs. 80

Between the side members of the frame 10 extends a seat-pivot bar or rod 30 that serves to pivotally sustain the chair seat. The ends of the pivot rod 30 pass through 85 the inner walls of the side members of the frame 10 and project a sufficient distance within these tubular members to afford a secure support for the seat.

The upper end of each of the rear legs of 90 the chair is provided with a supplemental plate that is preferably of angular form, each supplemental plate having a flange or member 35 that is riveted to the flange 23 of the corresponding rear leg and having a 95 flange or member 36 that projects at right angles to the member 35 and is perforated to receive a bar or rod 40, the ends of which project beyond the flange members 36 to enter guide grooves beneath the chair seat, as 100

will presently appear. In order to insure the accurate position of the rod 40 with respect to the flange members 36, a portion of the metal of the rod adjacent each side of the flanges 36 is squeezed up or offset by a suitable tool, as indicated at 41 in Figure 3 of the drawings, after the rod has been passed through the flanges 36. The flange member 36 of each of the supplemental plates at the upper end of the rear legs is formed with a slot 43 adapted to admit the rod 40 when the chair is in folded position, as will presently more fully appear.

The seat 50 of our improved chair is formed of thin sheet metal stamped in such manner that the edges of the seat depend and are turned inwardly, as at 51, thus affording great strength and rigidity to the seat and affording a broad edge therefor which cannot chafe or cut the garments of the user of the chair. As shown, the seat 50 is also formed with a centrally depressed portion 52, adapted, if so desired, to receive a pad or cushion, although when the chair is exposed to the weather this seat or cushion need not be employed.

Beneath and along the side edges of the seat 50 extend the guides 55. (See Figures 4 and 5.) These guides are preferably made as sheet metal channels spot welded in position beneath the side edge portion of the seat. Each of the guides 55 is formed with a long slot 56 and through these slots project the corresponding ends of the rod 40 that extends between the upper portions of the rear legs 20.

One of the objects of our invention is to insure that the chair when in folded position shall occupy as little space as possible. For this reason, the leg-pivot rods 17 and the seat-pivot rod 30 are arranged centrally with respect to the side members of the frame 10, and the flanged portions 21 of the rear legs 20 are arranged so that when the chair is folded, these flanged portions 21 will be between the side members of the frame 10 and the chair seat 50, which latter will overlap the flanged members 23 of the rear legs 20.

When the chair is in extended position as illustrated in Figure 1, it affords an exceedingly firm and comfortable support for the user. When the chair is to be folded or collapsed, it may be grasped by one hand at the top of the frame 10 and by the other hand at the front of the seat, and these parts will then be moved towards each other as indicated in Figure 2. As the parts are thus shifted, the ends of the rod 40 will move along the slots 56 of the guides 55 until the parts are in the position shown in Figure 4 of the drawings, at which time the seat and rear legs will be entirely between the side members of the frame 10. As the parts approximate the completely folded position,

the rod 40 will pass into the slots 43, and these slots 43 are so shaped or positioned with respect to the rod 40 that the walls of the slots will exert a frictional pressure upon the rod 40, tending to slightly deflect it. This frictional pressure will insure that when the parts are completely folded, as shown in Figure 4, the danger of the chair accidentally unfolding is avoided.

When the chair is used as a lawn chair or for outdoor purposes, it is not desirable to provide it with a cushion; but when used indoors or in positions where it is protected from the weather, a cushion for the seat 50 may be employed. We have provided a cushion adapted to be detachably connected to the chair, and this cushion is preferably formed of a base plate 60 of indurated fibre or the like, having a fabric cover 61 folded around the base plate 60 and secured thereto, and padding 62 interposed between the base plate 60 and the cover 61. To enable the cushion to be readily connected to and disconnected from the chair seat, we prefer to employ the means next to be described: At each of its corners, the base plate 60 of the cushion is formed with a slot having a broad portion 64 and a narrow portion 65, the broad portion 64 being of sufficient width to admit the head 66 of the metallic fastener, the stem of which fastener is shown as formed of bendable members 67. The depressed portion of the chair seat 50 is preferably perforated for ventilation, and certain of the holes in the depressed portion of the chair seat are adapted to coincide with the stem of the fasteners 67 (when these stems are in extended position), when the fasteners have been moved into the narrow portions 65 of the slots formed in the base plate 60 of the cushion. When a cushion is to be attached to the chair seat, the fasteners are first moved into the narrow portions 65 of the slots (see Figures 5 and 6) and the cushion is then placed within the depressed portion 52 of the chair seat, the extended stem portions 67 of the fasteners being placed through the holes in the chair seat coinciding therewith. The stems 67 of the fasteners are then bent (as shown in Figure 5) so as to securely retain the cushion in position for use.

While we have described what we regard as the preferred embodiment of our invention, it will be understood that the precise details may be varied without departing from the scope of the invention, and that features thereof may be used without its adoption as an entirety.

What we claim as our invention is:

1. A folding chair embodying a U-shaped metallic frame comprising the back member and front legs of the chair and a sheet metal brace plate extending between the side members of said frame, said brace plate

having an integrally rolled edge portion projecting at its opposite ends beyond the adjacent ends of said brace plate, embedded in said side members and welded thereto.

5 2. A folding chair embodying a U-shaped metallic frame comprising the back member and front legs of the chair, a seat-pivot rod extending between and having its ends embedded in the side members of said frame, 10 a metallic seat having depending flanges pivotally sustained by said rod to fold between said side members, a leg-pivot rod extending between and secured to said side members at a distance below said seat, and 15 angle iron rear legs including side flanges and crosswise extending flanges mounted on said last-mentioned rod and having their upper ends slidably connected to the side flanges of said seat, said rear legs being 20 adapted to extend between said side members and the seat when the seat is in folded position, and the crosswise extending flanges being disposed at the front edges of said side flanges and serving to engage portions 25 of the seat when in folded position, thereby to limit folding movement of said seat.

3. A folding chair comprising a frame forming the back member and the front legs of the chair, a seat formed of sheet metal 30 and having depending peripheral flanges integral therewith, a seat-pivot rod extending between the side members of said frame and through the depending side flanges of said seat, forwardly and rearwardly extending, 35 outwardly facing, channel shaped, slotted guide members, secured to the bottom of said seat inwardly of the depending side flanges thereof, and rear legs pivotally connected to the side members of said frame at a distance 40 below the seat, and having their upper ends slidably connected to said slotted guide members, said depending side flanges serving to conceal said guide members and the sliding connection of said leg members 45 thereto.

4. A folding chair comprising a frame forming the back member and front legs of the chair, a seat formed of sheet metal and having depending flanges integral therewith 50 at its sides and front, means pivotally connecting said seat flanges to the side members of said frame, guides carried by said seat adjacent the bottom thereof and located inside of said depending side flanges of the seat, and rear legs pivotally connected to the side members of said frame and having their upper ends slidably connected to said guides, said depending side flanges serving to conceal said guides and the connections 55 therewith of said rear legs.

5. A folding chair comprising a frame made of bent metal tubing and forming the back member and front legs of the chair, a seat-pivot rod and a leg-pivot rod extending 60 between the side members of said frame,

a seat pivotally sustained by said seat-pivot rod, said seat being formed of sheet metal and having rebent depending side flanges through which said seat pivot rod passes, guides adjacent the sides of the seat, located 70 between the bottom thereof and the rebent portion of the adjacent side flanges, rear legs formed of angle bars having side flanges adapted to extend between the leg members of the frame and the seat when the latter is in folded position, supplemental angle plates secured to the upper ends of said rear legs, a rod extending through the upper ends of said supplemental plates and into the guides beneath the seat, said rod being effective 75 to slidably connect the upper ends of said rear legs with said guide members, and said supplemental plates being formed with slotted portions to receive and frictionally engage said seat-pivot rod when the parts 80 are in folded position.

6. A folding chair comprising a frame forming the back member and front legs of the chair, a sheet metal seat having integral, depending front and side flanges, forwardly and rearwardly extending guide members secured to said seat and located on the bottom thereof inside of said side flanges, means extending through said depending side flanges and guide members adjacent 90 the rear end of the latter and into engagement with said front legs, for pivotally mounting the seat on said frame, and rear legs pivotally connected to said front legs 95 at a distance below the pivotal connections between said seat and front legs, and slidably connected inwardly of said side flanges to said guide members.

7. A folding chair comprising a frame forming the back member and front legs of the chair, a seat having depending side flanges, a pivot rod extending between said front legs and through said side flanges for pivotally mounting said seat on said back legs, a pair of slotted guide members carried 100 by said seat on the bottom thereof and respectively located inside of and adjacent said side flanges, angle iron rear legs pivotally connected to said front legs below said seat pivot rod and each having a crosswise extending front flange overlapping a side portion of the seat, and a side flange extending rearwardly from the outside edge of said front flange so as to fit between the 105 sides of said seat and the front legs when the chair is folded, and means for slidably connecting said rear legs to said slotted guide comprising supplementing angle plates having crosswise extending flanges 110 secured to the crosswise extending flanges of said rear legs and rearwardly extending flanges disposed inwardly of said guides, and a part projecting outwardly from said 115 inwardly disposed supplemental plate 120

125

130

135

flanges and slidably fitting in the slot of said slotted guide.

8. A folding chair comprising a frame forming the back member and the front legs of the chair, a seat formed of sheet metal and having depending peripheral flanges integral therewith, a seat-pivot rod extending between the side members of said frame and through the depending side flanges of said seat, forwardly and rearwardly extending, outwardly facing, channel-shaped, slotted guide members, secured in position beneath the seat and located inwardly of the depending flanges, and rear legs pivotally connected to the side members of said frame at a distance below the seat and having their upper ends slidably connected to said slotted guide members, said depending side flanges serving to conceal said guide members and the sliding connection of said leg members thereto.
